The ornamental design for a plant rack, as shown and described.

DESCRIPTION

FIG. 1 is a perspective view of a plant rack showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a partial enlarged view of portion 9 in FIG. 1; and, FIG. 10 is a partial enlarged view of portion 10 in FIG. 2. The dash-dot broken lines encircling a portion of the plant rack in FIGS. 1 and 2 and the enlarged views in FIGS. 9 and 10 are boundary lines and form no part of the claimed design.
